UNITED STATES PATENT OFFICE.

CHARLES M. TINSMAN, OF LURAY, AND STERLING S. BALL, OF KAHOKA,
MISSOURI.

WIRE-FENCE TOOL.

SPECIFICATION forming part of Letters Patent No. 566,249, dated August 18, 1896.

Application filed November 29, 1895. Serial No. 570,490. (No model.)

To all whom it may concern:

Be it known that we, CHARLES M. TINSMAN, residing at Luray, and STERLING S. BALL, residing at Kahoka, in the county of Clark, 5 State of Missouri, citizens of the United States, have invented a new and useful Combination Wire-Fence Tool, of which the following is a specification.

This invention relates to an improvement 10 in combination-tools, and is especially designed for use in the construction or repair of wire fences.

The objects of the present invention are to provide a simple, inexpensive, and efficient 15 device of the character referred to which shall combine a wire-cutter, a staple puller and driver, a vise for clamping the contiguous ends of the wires to be spliced, and which, at the same time, may be used as a 20 hand-vise for clamping any article desired and holding the same without the aid of hand-pressure. These and other objects will be more fully explained in the ensuing description.

25 The invention consists in an improved combination-tool embodying certain novel features and details of construction and arrangement of parts, as hereinafter fully described, illustrated in the drawings, and 30 finally pointed out in the claims.

In the accompanying drawings, Figure 1 is a perspective view of the improved tool with the jaws open and the wire-twister combined therewith in such manner as to adapt 35 the device to act in the capacity of a hand-vise. Fig. 2 is a side elevation of the same, showing the wire-twister secured to one of the hand-levers and extending longitudinally therewith. Fig. 3 is an enlarged detail 40 perspective view of the wire-twister. Fig. 4 illustrates the manner in which the two members of the device are utilized in the formation of a splice.

Similar numerals of reference designate 45 corresponding parts in the several figures of the drawings.

Referring to the accompanying drawings, 1 and 2 designate a pair of handles, formed, preferably, of steel, and each provided at one 50 end with a jaw 3. These handles are pivotally connected at a point 4 in proximal rela-

tion to the jaws 3 in order to afford the desired leverage for securely and firmly clamping the ends of wires or other objects between said jaws. The working or active 55 faces of the jaws 3 are formed with transverse registering grooves 5, which are adapted to receive and partially embrace the wire or wires introduced between the jaws, the inner pair of grooves or those lying next adjacent 60 to the pivot 4 being adapted to receive and hold the main or longitudinal fence-wire while making a splice.

The jaws 3 are expanded transversely in such manner as to overlap the shank portions 65 of the handles, and are each provided with an integral bill 6. These bills project beyond the ends of the jaws and converge toward their points, and these points interlap or extend slightly beyond each other, whereby they 70 are adapted, when opened, to be passed through a staple, and when closed to prevent any possibility of said bills accidentally slipping or becoming disengaged from the staple in the operation of extracting the latter from 75 the fence-post. Under this particular arrangement of staple-extracting bills the two may be vibrated either upward or downward upon the rounded outer edges of the bills as fulcrums for drawing a staple. 80

7 indicates a poll used for driving the staples or other fasteners.

The handles 1 and 2 are further provided adjacent to the pivot 4 with rounded notches 8, the bases of which are reversely inclined 85 in order to establish acute cutting edges 9. A length of wire passing through and resting in said notches will thereby be retained and prevented from slipping out of the crotch between the handles while the latter are being 90 vibrated for the purpose of severing the wire. At points intermediate their ends the handles 1 and 2 are deflected in reverse directions, so as to bring the rear portions of said handles into transverse alinement with each 95 other, and the extremities of said handles are each provided with longitudinal slits or incisions 10, extending approximately half the length of the handles, and the divided portions of the handles are formed at two or more intervals with transversely-alining threaded openings, into which are inserted

set-screws 11. The divided portions of each handle are spread apart, so as to leave an intervening space, which, however, may be closed with the aid of the set-screw 11, thus adapting said handle to be utilized as a clamp or vise for engaging wires or small articles.

12 designates the wire-twister, which is composed of a section of bar iron or steel having near one end a central longitudinal slot 13, through which the set-screws 11 are adapted to pass when the twisting-plate is introduced between the divided portions of the handles in the manner shown in Fig. 1. The twister is also formed at each end with a pair 15 of curved fingers 14 and 15, the one, 14, being substantially U-shaped or recurved upon itself and the other, 15, being of quadrantal form and curved in the same direction or upon the same side of the body of the twisting-plate as the finger 14. These fingers are spaced apart, as shown, and the intervening portion of the body of the plate is formed with a rounded concavity or slideway 16 for facilitating the slipping of the short end of 25 the wire while making a splice, as hereinafter explained. The fingers 14 and 15 at one end of the twisting-plate are located further apart than at the other end and the concavity 16 correspondingly increased in width. This 30 adapts the device the better to wire of different gages.

The operation of the device as regards the cutting of wire and the pulling and driving of staples will be readily understood from the 35 foregoing description.

The manner in which the twisting-plate adapts the other part of the tool to be used in the capacity of a hand-vise is clearly illustrated in Fig. 1, under which arrangement 40 by adjusting one or both of the binding-screws 11 the jaws 3 may be firmly held at any desired point.

When the device is employed for the purpose of making a splice in the line-wires of 45 the fence, the overlapping ends of the wire are engaged between the jaws 3 and firmly held therein while the twister is applied and used. The twister is applied as shown in Fig. 4, wherein the U-shaped finger 14 is seen 50 to embrace both wires, or rather both ends of the wire to be spliced. This finger 14 is placed against the sides of the jaws 3 and the short end of the wire is then placed between the fingers 14 and 15, so that it passes beneath 55 the finger 14 and over the finger 15. The twister is now rotated, so that the end of the wire will ride in the concavity 16 between the two fingers, and it will continue to ride therein until it has been twisted one or more

times around the main wire. This operation 60 is repeated upon the reverse side of the jaws 3, whereupon the splice is completed. In splicing the ends of heavy or barbed wire, the twister is used in a reverse position to that shown in Fig. 4, or with the finger 15 65 next to the jaws 3. When used for driving staples or other fasteners, the twisting-plate 12 may be fastened to one of the handles in the manner indicated in Fig. 2, so that it will be held in place and the liability of jarring 70 the same loose obviated.

It will thus be seen that a very simple, convenient, and efficient combination-tool is produced, which, while especially useful in the construction and repair of wire fences, is also 75 applicable to various other uses which will readily suggest themselves to the mind.

It will also be apparent that various changes in the form, proportion, and minor details of construction may be resorted to without departing from the spirit or sacrificing any of the advantages of this invention.

Having thus described the invention, what is claimed as new is—

1. The herein-described twisting device, 85 comprising a bar or plate provided at one end with two fingers, one of which is curved to partially embrace the wire to be spliced, and the second finger spaced apart from said finger and adapted to pass between the interlapping ends of the wire and to deflect the short end of the wire and in the revolution of the twister to coil or twist said end one or more times around the other portion of the wire, substantially as described. 95

2. The combination with the handles crossed and pivotally connected as described and formed as to their ends with longitudinal slits or divisions, and the clamping-jaws forming part of said handles, of a bar inserted 100 between the divided portions of the handles and provided with a longitudinal slot and the clamping-screws passing through the handles and also through said bar, one of the screws working in the longitudinal slot of said bar, 105 substantially as described.

In testimony that we claim the foregoing as our own we have hereto affixed our signatures in the presence of two witnesses.
